[57] CLAIM

The ornamental design for a socket terminal, as shown and described.

DESCRIPTION

FIG. 1 is a perspective view of the front, one end and one side of a socket terminal showing our new design; FIG. 2 is a front plan view thereof; FIG. 3 is a side elevational view thereof of said one side, the opposite side being a mirror image thereof; FIG. 4 is an end view of said one end; FIG. 5 is an end view of an opposite end; and, FIG. 6 is a rear elevational view thereof.

*FIG. 1**FIG. 2**FIG. 3**FIG. 4**FIG. 5**FIG. 6*
